FIG. 4.

INVENTOR

Jacob H. Liederman

By Ralph Kalish, Atty.

UNITED STATES PATENT OFFICE.

JACOB H. LIEDELMAN, OF ST. LOUIS, MISSOURI.

CAP OR HEADWEAR.

1,266,503.

Specification of Letters Patent. Patented May 14, 1918.

Application filed September 19, 1917. Serial No. 182,111.

To all whom it may concern:

Be it known that I, JACOB H. LIEDELMAN, a citizen of the United States, residing at the city of St. Louis, State of Missouri, have invented a certain new and useful Improvement in Caps or Headwear, of which the following is a specification, reference being had to the accompanying drawing, forming a part thereof.

10 This invention relates to a certain new and useful improvement in caps or headwear.

With vizored caps as heretofore generally constructed, so far as I am aware, the vizor, 15 while useful as a shade in shielding the eyes from sun-glare, interferes more or less with the sight, and this is particularly true when the cap is pulled down upon the head to bring the vizor more closely in front of the 20 eyes to protect the eyes from dust and the like. The principal object of my present invention is to provide a cap having a convertible vizor composed of a transparent member or vizor proper and a non-transparent semi-removable flap-covering there- 25 for, the flap normally resting upon and concealing the vizor proper and the cap then presenting the appearance of the ordinary cap with the vizor useful merely as a non- 30 transparent shield for the eyes. When, however, the cap is pulled down upon the head and the flap turned up and the transparent vizor-member thus exposed, the vizor is converted into a combination shield and window 35 for the eyes, the vizor being then useful both as a dust and sun shield and as a window for the eyes in aid of vision.

With the above and other objects in view, 40 my present invention resides in certain novel features of form, construction, arrangement, and combination of parts, all as will herein- 45 after be described and afterward pointed out in the claims.

In the accompanying drawing,

45 Figure 1 is an elevational view of a cap embodying my invention, the cap being shown as normally worn with the vizor-flap turned down and the transparent vizor-member covered or concealed;

50 Fig. 2 is an enlarged fragmentary sectional view of the cap as shown in Fig. 1;

Fig. 3 is also an elevational view of the cap, the cap, however, being shown as ab- 55 normally worn with the vizor-flap turned up and the transparent vizor-member exposed; and

Fig. 4 is an enlarged fragmentary sec- 60 tional view of the cap as shown in Fig. 3.

Referring to the said drawing, in which like reference characters refer to like parts throughout the several views, 1 indicates the body-portion of the cap, which may be of any suitable preferably flexible material and which is preferably inturned or folded upon itself at its lower edge, as at 2.

3 indicates the inner or so-called sweat- 65 band of the cap, which is also preferably folded upon itself at its lower edge, as at 4.

The vizor of the cap comprises a suitably shaped section 5 of any suitable preferably 70 flexible transparent material, such as sheet celluloid, and a correspondingly shaped flexible covering-flap. At and along its upper edge, the section 5 has fixed thereto, as by thread-stitches or the like 6, short sec-

75 tions 7 of any suitable flexible material, preferably of the same material as that of which the body-portion 1 is composed, which sections 7 are adapted to form and provide what might be described as a hinge 80

or securing-member for transparent vizor- 85 section 5. And, further, the vizor-section 5 being hingedly fastened, as described, to the body-member 1, both the covering-flap and the vizor-section 5 may be swung or moved 90

together into an approximately upright po- 95 sition relatively to the body-member 1, or approximately into the position shown with respect to the covering-flap in Figs. 3 and 4, the cap being thereby converted into sub- 100 stantially what might be called a vizorless cap. The outer marginal edge of section 5 is preferably for neatness and protection covered, as shown, by a binding or tape 8.

The covering-flap includes preferably an 105 outer or upper section 9 preferably also of the same material as that of which body-portion 1 is composed, and an inner or under section 10 of suitable material preferably

green in color and hence comfortable to the 110 eyes. The upper edges of the sections 9 and 10, as well as also the upper edges of the sections 7, are interposed within body-portion 1 between the inturned edge 2 of body-portion 1 and the inturned edge 4 of band 3, 105

and all said parts secured together, as by thread stitches or the like 11, preferably in one operation. The sections 9 and 10 are preferably inturned or folded upon them- 110 selves at their free edge and sewed or other- wise secured together, as shown.

My new cap is adapted to be normally

used or worn as the ordinary cap, as shown in Fig. 1. When so worn, the vizor-proper 5 provides a support for the covering-flap, which latter is adapted to normally rest upon and cover or conceal the transparent vizor-section 5, and with the flap in such position, my new combination vizor serves merely, as in the ordinary cap, as a shade for shielding the eyes from sun-glare and the like. In motoring, however, for instance, a cap of this type is usually pulled down upon the head and the vizor correspondingly brought more closely in front of the eyes, so as to then also shield the eyes from dust and the wind. When the cap is so pulled down upon the head, the covering-flap is turned up into the position thereof shown in Figs. 3 and 4, being retained in such position by the tension of the cap upon the head, and the transparent vizor-section thus fully exposed, the transparent vizor-section then forming and providing a shield for fully protecting the eyes from sun-glare, dust, the wind, and the like, but also serving as a window for clear, unobstructed vision.

I am aware that minor changes in the form, construction, arrangement, and combination of the several parts of my new cap may be made and substituted for those herein shown and described without departing from the nature and principle of my invention.

Having thus described my invention, what I claim and desire to secure by Letters Patent is:

1. As a new article of manufacture, a cap or the like including a body-portion and a vizor, the vizor comprising a transparent

section hingedly fastened to the body-portion and a non-transparent flexible flap also fastened to the body-portion and adapted to normally rest upon and cover the transparent section, the transparent section and covering flap being movable together into an approximately upright position relatively to the body-portion and the flap being further adapted to be separately turned up to expose the transparent section and the transparent section being then adapted when brought down in front of the eyes to provide a shield and window for the eyes.

2. As a new article of manufacture, a cap or the like including a body-portion, a section of flexible material fixed to and along the lower front edge of the body-portion, a transparent vizor-section fixed to said section, said section providing a hinge between the transparent vizor-section and the body-portion, whereby the vizor-section may be swung relatively to the body-portion, and a flexible flap also fixed to the lower front edge of the body-portion and adapted to normally rest upon and conceal the transparent vizor-section, the transparent section and flap being both movable into an approximately upright position relatively to the body-portion and the flap being further separately movable to upright position to expose the transparent section and the transparent section being then adapted when brought down in front of the eyes to provide a shield and window for the eyes.

In testimony whereof, I have signed my name to this specification.

JACOB H. LIEDERMAN.
